PLIER ATTACHMENT

Clifford E. Cressy, 311 Duluth,
Highland, Ind. 46322

Filed May 6, 1965, Ser. No. 85,147

Term of patent 14 years

(Cl. D54—13)

FIG. 1

FIG. 2

FIG. 4

FIG. 3

FIG. 5

FIGURE 1 is a perspective view of a plier attachment, embodying the present design;

FIGURE 2 is an end elevational view of the plier attachment shown in FIGURE 1;

FIGURE 3 is a bottom view of the plier attachment shown in the preceding figures;

FIGURE 4 is a side elevational view opposite to that shown in FIGURE 1; and

FIGURE 5 is an end elevational view opposite to that shown in FIGURE 2.

I claim:

The ornamental design for a plier attachment, substantially as shown.
